UNITED STATES PATENT OFFICE.

CHARLES L. RICHARDS, OF FALUN, KANSAS, ASSIGNOR OF ONE-HALF TO
JESSE Y. HUDSON, OF FALUN, KANSAS.

THRESHING-MACHINE ATTACHMENT.

SPECIFICATION forming part of Letters Patent No. 734,751, dated July 28, 1903.

Application filed September 11, 1902. Serial No. 123,007. (No model.)

To all whom it may concern:

Be it known that I, CHARLES L. RICHARDS, a citizen of the United States, residing at Falun, in the county of Saline and State of Kansas, have invented a new and useful Threshing-Machine Attachment, of which the following is a specification.

This invention relates to band-cutting and feeding attachments for threshing-machines; and it has for its object to provide a device of this class which shall possess superior advantages in point of simplicity, durability, and general efficiency.

With these ends in view the invention consists in the improved construction, arrangement, and combination of parts, which will be hereinafter more fully described, and particularly pointed out in the claims.

In the accompanying drawings, Figure 1 is a sectional elevation illustrating my invention applied to a threshing-machine in operative position. Fig. 2 is a plan view showing the cutter-bars, the shafts supporting the same, and related parts. Fig. 3 is a sectional elevation taken on the line 3-3 in Fig. 2.

Corresponding parts in the several figures are indicated by similar numerals of reference.

1 designates a part of the casing of a threshing-machine, of which 2 designates the cylinder, and 3 the concave.

4 designates the feed-table, the upper side of which is preferably serrated, as shown at 5, and which is disposed to receive the usual vibratory motion by means not illustrated in the drawings. The front end of the feed-table is supported upon a portion of the casing, as 6.

7 designates a crank-shaft which is supported in suitable bearings in the sides of the casing and which is provided between said sides with two cranks 8, extending in opposite directions from the axial line of the shaft. This shaft is provided at one of its extended ends with a pulley 9, by means of which it receives motion from the source of power. At its opposite end the said crank-shaft carries a governor 10 to regulate the speed thereof. This governor may be of any suitable approved construction, and as it forms no part of my present invention it does not need to be described in detail.

A pair of cutter-bars 11 are supported by means of boxes 12 upon the cranks 8 of a shaft 7. Each of these cutter-bars is composed of three separate pieces 13 14 14, the front section 13 of each cutter-bar being interposed between the front ends of the adjacent sections 14 14, beyond which it extends, as will be clearly seen in Fig. 2 of the drawings. The rear ends of the said cutter-bars are supported by means of stirrups or links 15, provided at their ends with cranks 16, engaging boxes 17, that are suitably supported under the top of the frame or casing of the machine, said stirrups being journaled in boxes 18 upon the rear ends of the members 14 of the cutter-bars.

Each of the cutter-bars carries a set of four cutters 19, each being composed of a curved bar 20, having teeth 21 and connected with the cutter-bar by means of a link or brace 22, which may be of any desired length, so as to dispose the said cutters at any desired distance below the cutter-bars. Provision may be made for adjustment of the cutters by providing each of the braces 22 with a plurality of perforations 23 to receive the fastening pin or bolt 23^a.

24 designates the endless carrier, which may be said to constitute the feed-table proper and upon which the sheaves are placed in position to pass under the cutters and under the vibrating pan 4, from which the grain is fed to the cylinder. This endless carrier is supported upon the front and rear shafts, designated, respectively, 25 and 26, the latter of which may be withdrawn and replaced in auxiliary bearings 27, so as to raise or lower the rear end of said carrier, as may be found necessary or desirable. A brace-rod 28 adjustably connects the front end of the endless carrier with the framing or casing of the machine, and it is preferred to construct the said carrier with a hinge 29, which shall enable said carrier to be folded while in transit. The rear ends of the compound cutter-bars are provided with feed-plates 30, which may be constructed either of wood or metal and which are provided with deep cuts or serrations, as 31, which being disposed directly above the rear discharge of the endless carrier and above the vibrating pan 4 will greatly assist in feeding the grain to and preventing

it from passing over the cylinder. These plates are firmly secured to the sides of the rear ends of the members 14 of the cutter-bars, and provision may be made, if desired, 5 for the vertical adjustment of the rear ends of said feed-plates—for instance, by providing them with slots 32 for the passage of the clamping-bolts 33.

It will be observed that by the construction 10 and arrangement of parts herein shown and described each cutter-bar is provided with a set of four band-cutters disposed equidistantly laterally, while two of the band-cutters of each set are disposed in front and in 15 rear of the two remaining ones, the arrangement being such, as will be seen by reference to the drawings, that the band-cutters secured to the outer sides of each cutter-bar are in alinement with each other, while those set 20 cured to the central member of each cutter-bar or between said central member and the outer members are disposed, respectively, in front and in rear of the outside cutters, thereby covering a large area and making it practically impossible for a single sheaf to pass 25 the device without having its band cut. This is a matter of considerable importance, inasmuch as serious accidents are frequently caused by the attempt to cut the bands of 30 sheaves in transit which have escaped the band-cutting mechanism. The feed-plates are likewise disposed in the positions in which they may most effectively exercise the functions for which they are provided.

35 The operation of this invention and its advantages will be readily understood from the foregoing description, taken in connection with the drawings hereto annexed. The crank-shaft imparts to the cutter-bars supported thereon a forwardly and rearwardly, as well as an upwardly and downwardly, reciprocating motion, whereby the cutters mounted upon said bars are caused to cut the bands of the sheaves fed underneath them 40 by means of the endless carrier 24, upon the front end of which they are placed by the operator. The speed of the crank-shaft 7 will be governed by the governor 10. The discharge end of the endless carrier may be 45 adjusted vertically, so as to bring its upper or carrying surface at a greater or less distance from the band-cutters and the grain,

the bands having been cut, will pass onto the vibratory pan 4, by means of which it is distributed and fed equally to the cylinder of 55 the machine.

Having thus fully described my invention, I claim and desire to secure by Letters Patent of the United States—

1. In a device of the class described, a cutter-bar composed of a forwardly-extending central member and rearwardly-extending outer members, said members being firmly connected together, and cutters secured adjustably to the outer sides of the outer members and to the outer sides of the central member, the cutters secured to said central member being disposed respectively in front and in rear of those secured to the outer members. 60

2. In a device of the class described, a cutter-bar composed of a forwardly-extending central member and rearwardly-extending outer members, said members being firmly connected together, cutters secured adjustably to the outer sides of the outer members and to the outer sides of the central members, the cutters secured to said central member being disposed respectively in front and in rear of those secured to the outer members, 65 a crank-shaft supporting the front ends of said cutter-bars, feed-plates secured to the outer sides of the rearwardly-extended members, and stirrups connecting said rearwardly-extended members of the cutter-bars flexibly 70 with the frame of the machine.

3. In a device of the class described, a cutter-bar composed of a forwardly-extending central member and rearwardly-extending outer members, said members being firmly bolted together and carrying band-cutting knives, in combination with downwardly-extending serrated teeth-plates secured to the outer sides of the outer members at the rear ends thereof, and means for adjusting 95 the dip of said serrated plates.

In testimony that I claim the foregoing as my own I have hereto affixed my signature in the presence of two witnesses.

CHARLES L. RICHARDS.
